MAX C. BATSEL, OF WILKINSBURG, PENNSYLVANIA.

WIRELESS TRANSMISSION SYSTEM.

Application filed January 25, 1921. Serial No. 439,857.

To all whom it may concern:

Be it known that I, MAX C. BATSEL, a citizen of the United States, and a resident of Wilkinsburg, in the county of Allegheny and State of Pennsylvania, have invented a new and useful Improvement in Wireless Transmission Systems, of which the following is a specification.

My invention relates to improvements in transmitting apparatus for wireless telephone and telegraph systems and more particularly to means for coupling the amplifying circuit to the radiating circuit.

An object of my invention is to provide a system of amplifier circuits, comprising a vacuum-tube generator and an amplifier, with means to couple the amplifier circuit to the radiating system.

Another object is to provide a coupling between an oscillating system and a radiating system that will keep the current in the amplifying system within safe values when the radiating system is untuned to the frequency of the oscillating circuit but which will have the correct impedance when the two systems are tuned to the same frequency, for the desired output.

In operating vacuum-tube amplifiers with loose coupling and low values of resistance in the plate-circuit coil, it has been customary to insert resistance in the plate circuit of the amplifier tube or tubes to prevent the generation of destructive currents in the plate circuits when the radiating system is untuned to the frequency of the oscillating circuit. The plate circuit has a direct-current flow therein, as a result of the plate battery or generator. In addition to this direct current there is superimposed an alternating current due to the oscillating voltage impressed upon the grid of the tube. Before the radiating system, comprising the antenna circuits, is tuned to the same frequency as the vacuum-tube amplifier there is but small load placed upon the plate circuit of the amplifier tube. This has frequently resulted, heretofore, in an alternating current of sufficient value to destroy the tube.

In order to take care of these heavy currents, resistance has customarily been inserted in the plate circuit of the tube and kept in circuit until the radiating system, comprising the antenna circuits, was tuned to the oscillating frequency. The resistance has then been taken out of the plate

circuit of the amplifier tube, and the effective load of the tuned antenna circuit prevented currents of dangerous value from flowing in that plate circuit. If, through haste or negligence, resistance was not inserted, the tube would be destroyed.

Another expedient which has been tried, but which proved to be impracticable, was to enlarge the inductance, that acts as the primary of a loose-coupling transformer, in the plate circuit of the amplifier tube, to a value sufficient to reduce the effective current in the plate circuit to a safe value. It has been found that, when the inductance was of large enough value to accomplish this purpose, there was a large wattless component of the plate current which existed when the antenna was tuned and coupled to the amplifier tube circuit. This wattless component of the plate current represented energy lost in heat and so considerably limited the percentage of efficiency of power out-put.

The present invention makes it possible to use a large inductance in the primary coil of the transformer and yet avoids the disadvantage of a large wattless component of the plate current when the antenna is tuned.

My system employs a generator or oscillating tube and an amplifier tube. The amplifier tube is connected to the radiating system by means of a power transformer containing iron, steel or a similar substance or simply an air core. The transformer used is one having small leakage flux, and hence, small leakage reactance. This power-transformer coupling between the amplifying system and the radiating system insures that, when the radiating system is out of tune with the amplifying system, the current flowing in the amplifying system will not be of excessive value; yet, when the two are coupled and tuned to the same frequency, the magnetizing current is but a small percentage of the total power output of the amplifier tube. This is because, when the radiating system is detuned, practically all of the large primary inductance is available to impede the plate current but when it is tuned, the only inductive effect of the transformer in the plate circuit is the small one due to leakage.

In the drawings:

Figure 1 is a diagrammatic view of a system embodying a transmitting apparatus employing my power-transmitting cou-

pling between the amplifying system and the radiating system.

Fig. 2 is a diagrammatic view of the circuits of a vacuum-tube amplifier.

5 Fig. 3 is a diagram representing the flow of the plate current in a circuit such as is represented in Fig. 2.

10 Fig. 4 is a diagrammatic view of a vacuum-tube amplifier in which a source of alternating current is used to change the potential of the grid.

15 Fig. 5 is a diagram illustrating the plate current generated in the plate circuit of the tube shown in Fig. 4.

20 In Fig. 1, the numeral 1 designates a vacuum tube having a filament element 2, a grid element 3 and a plate element 4. The filament element 2 is heated by means of a suitable battery 5, and a source of direct current 6, shunted by a condenser 6', supplies direct-current to the plate circuit of the vacuum tube through a choke coil 7.

25 The tube 1 is a generator tube and oscillates with a frequency determined by the values of capacitance and inductance in the oscillating circuit comprising a variable inductance 8 and capacitances 9 and 10. Coupled to the oscillating circuit, comprising the variable inductance 8 and capacitances 30 9 and 10, through a condenser 11, is the grid 3 of the generator tube 1. A grid-leak resistance 12 performs the usual function of grid-leak resistances in generator tubes.

35 An amplifier tube 13, having a filament element 14, a grid element 15 and a plate element 16, is shown with its plate circuit supplied by the same source of direct-current 6 that supplies the plate circuit of the generator tube 1. The grid 15 of the tube 40 13 is coupled, through a condenser 17, to the oscillating circuit comprising the variable inductance 8 and capacitances 9 and 10. A suitable grid-leak resistance 18 is in circuit between the filament 14 and the grid 15.

45 The battery 5 supplies current for heating the filament 14 which is connected in parallel with the filament 2. Any number of tubes may be connected in parallel, as amplifiers, to obtain large power output.

50 In the plate circuit of the amplifier tube 13, is located an inductance 20, forming the primary of a transformer 21 to couple the amplifying system to the radiating system. The secondary of the transformer 21 com-

55 prises an inductance 22 which is closely coupled to the inductance 20 which forms the primary of the transformer. The two windings are either wound on a suitable iron or steel core as illustrated at 23, or they may 60 be interleaved or constructed in a special manner (not shown) to produce an exceptionally close coupling or small leakage flux. The inductance 22 lies in the radiating circuit comprising an antenna 24, a variable inductance 25 and the inductance 22 above

mentioned to ground. When I speak of an iron core 23, it is to be expressly understood that I mean any of the special irons, steels or other metals used in power-transformer construction.

70 In Fig. 2 is shown an electron tube in which a filament element 30 is heated by an "A" battery 31, and the plate-filament circuit, comprising the filament 30 and a plate 75 32, is supplied with a "B" battery 33. Applying a constant negative potential to a grid 34, is a "C" battery 35 the negative terminal of which is connected to the grid.

80 Fig. 3 shows the type of current flowing in the plate-filament circuit. In the diagram shown in Fig. 3, current is the ordinate and time the abscissa. There is a constant value of plate current, as denoted by the straight line I_p .

85 In Fig. 4 is shown an electron tube like that shown in Fig. 2 to which is added a source of alternating-current 36 to cause the value of the grid potential to fluctuate through certain limits.

90 Fig. 5 diagrammatically shows the fluctuations in value of the plate current for the system illustrated in Fig. 4. When a source of alternating potential of sufficient amplitude is placed in the grid-filament circuit, the plate current is caused to vary in accordance with the values shown in curves A, B, C and D. The effective value of the plate current is represented by the dotted line I . From this diagram, it is apparent that, if it were not for the high impedance 100 of the coil 20, the effective values of the plate current would be greatly increased when there is no substantial load placed upon the plate circuit of the vacuum tube and when a source of alternating potential 105 of sufficient amplitude is inserted in the grid-filament circuit.

110 The effective value of plate current, under the circumstances just described, might be great enough to destroy the vacuum tube. Therefore, it has been customary, before the antenna circuit or radiating system was tuned to the frequency of the out-put oscillations of the tube, to insert a resistance in the plate-filament circuit of sufficient value 115 to act as an impedance to cut down the effective value of the plate current to a safe limit for the tube used. This insertion of resistance was liable to be neglected, with resulting destruction of the tube.

120 Let us suppose that, in the case represented in Fig. 4, the primary of a transformer has been placed in the plate-filament circuit of the tube which has a relatively high primary inductance of sufficient magnitude to cut down the effective plate current to a safe value. This inductance must be high enough to take care of the effective plate current when the radiating system is not in tune with the current in the oscillating cir- 130

cuit. This means that the only current traversing the plate-filament circuit will be the normal exciting current of the transformer. With the radiating system un-tuned, the resistance of the radiating system is such that substantially no energy is radiated from the antenna circuit.

But, when the radiating system is tuned to the frequency of the oscillating system and my transformer is working under load, the power lost in magnetizing current is a negligible factor, in proportion to the power expended in taking care of the load in the secondary. Hence, the functioning of the transformer which I employ is peculiarly suited to obtain good results for two reasons; first, when the radiating system is not tuned to the frequency of the oscillating system, the plate current is held within safe limits; second, when the oscillating system and radiating system are tuned to the same frequency; in other words, when the load has been put upon the plate circuit, only a negligible fraction of power is lost because of the magnetizing current of the transformer.

In operation, the generator tube 1 is producing fluctuations in its plate circuit in accordance with a given frequency regulated by the period of the tuned circuit which includes the variable inductance 8 and the capacitances 9 and 10. Suitable conditions for sustained oscillations are present by reason of the static coupling of the grid 3 of the generator tube 1, through the capacitance 11, to the tuned circuit comprising the variable inductance 8 and the capacitances 9 and 10 lying within the plate circuit of the tube. The tube 13 produces amplified oscillations, because the grid 15 of this tube is statically connected, through the condenser 17, to the tuned circuit comprising the variable inductance 8 and the capacitances 9 and 10.

The primary 20 of the transformer 21 lies within the plate circuit of the amplifier tube 13, and, when the radiating system comprising the antenna 24, the variable inductance 25, and the secondary inductance 22 of the transformer 21, is out of tune with the frequency generated, the current in the plate-filament circuit of the amplifier tube 13 is held within safe values. This condition obtains largely by reason of the counter-electromotive force generated in the inductance 20 of the transformer. When the radiating system, however, is tuned to the same frequency as the oscillating system, the transformer 21 is working under load and the power output of the plate circuit of the tube 13 is practically all consumed in producing current in the radiating system.

By employing a power-type transformer to couple the plate circuit of the amplifier tube to the radiating system, I have provided

an automatic check for limiting the effective value of the plate current flowing, before the radiating system has been tuned to the out-put frequency. Not only have I accomplished an automatic regulation of the plate current of the amplifier tube to within safe values, but I have done this without materially lessening the power output because the loss due to the magnetizing current of the transformer becomes negligible when the transformer is working under load.

Since I have not shown all the possible modifications of my invention which will occur to those skilled in the art, I desire that my invention shall be limited only by the scope of the appended claims or the showing of the prior art.

I claim as my invention:

1. A system for transmitting oscillations comprising an amplifying system, a radiating system, and means for coupling the amplifying and radiating systems to ensure a relatively high impedance in the amplifying system when the two systems are untuned with respect to each other. 90

2. A system for transmitting oscillations comprising an amplifying system, a primary of a transformer having low leakage flux in the amplifying system, a radiating system and a secondary of the transformer 95 in the radiating system to ensure a relatively high impedance in the amplifying system when the two systems are untuned with respect to each other.

3. A system for transmitting oscillations 100 comprising an oscillating system, an amplifying system, an inductance forming the primary of a transformer in the amplifying system, a radiating system, an inductance in the radiating system forming the 105 secondary of the transformer and means producing a large counter-electromotive force in the primary when the systems are untuned with respect to each other.

4. A system for transmitting oscillations 110 comprising an oscillating system, an amplifying system, a radiating system and an iron core power transformer coupling the two latter systems.

5. A system for transmitting oscillations 115 comprising an oscillating system, an amplifying system, a radiating system and means coupling the amplifying and radiating systems having a large self inductance when the two systems are untuned with respect to each other and but small power loss when they are in tune. 120

6. In a radio sending system, an oscillating circuit, an amplifying circuit, a radiating circuit and a transformer of the power 125 type having a high primary inductance in the amplifying circuit and a secondary inductance in the radiating circuit, and said transformer having a close coupling, whereby a high impedance will be present in the 130

- primary circuit when the transformer is without load.
7. A system for transmitting oscillations comprising an oscillating system having a generator tube and an amplifier tube in which the plate circuits of the amplifier and generator tubes are conductively connected; a radiating system and a power transformer drawing exciting currents coupling the two systems.
8. A system for producing radio oscillations comprising an oscillating system having a generator tube and an amplifier tube, the plate circuits of the amplifier and generator tubes being conductively connected and the grids of the tubes being statically connected to the plate circuits, a radiating system, an inductance forming the primary of a transformer in the amplifying system, an inductance forming the secondary of the transformer in the radiating system and means operatively associated with said inductances tending to produce a relatively large counter-electromotive force in the plate circuit of the amplifier tube when the systems are untuned with respect to each other.
9. A system for producing radio oscillations comprising an oscillating system having a generator tube and an amplifier tube, the plate circuits of the generator and amplifier tubes being conductively connected and the grids of the tubes statically connected to the plate circuits, a radiating system and an iron core power-type transformer having a primary inductance in the oscillating circuit and a secondary inductance in the radiating circuit.
10. In combination, a power circuit carrying radio-frequency currents, an outgoing circuit, and coupling means therebetween comprising a magnetizable member and primary and secondary energizing windings therefor, one of said windings being included in said power circuit and constituting substantially the whole of the inductance therein, the other of said windings being included in said outgoing circuit.
11. In combination, a power circuit carrying radio-frequency currents, an outgoing circuit and a coupling between said circuits including an iron core transformer having a primary winding included in said power circuit and a secondary winding included in said outgoing circuit said primary winding constituting the major part of the inductance in the power circuit and said secondary winding constituting a minor part of the inductance in said outgoing circuit.
12. In a radio system, an oscillating circuit, a power circuit controlled thereby, an antenna circuit and an inductive coupling between said power circuit and said antenna circuit, said coupling including an inductance in the power circuit and an inductance in the antenna circuit, said inductances being closely coupled together, said antenna circuit also including means for tuning it to the frequency of the oscillating circuit and said tuning means including an inductance.

In testimony whereof, I have hereunto subscribed my name this 31st day of December 1920.

MAX C. BATSEL.
